ATTORNEY

UNITED STATES PATENT OFFICE.

DAN G. SCHAFER, OF BRANCH COUNTY, MICHIGAN.

STANCHION.

1,286,425.

Specification of Letters Patent.

Patented Dec. 3, 1918.

Application filed November 30, 1917, Serial No. 204,729. Renewed August 22, 1918. Serial No. 251,009.

To all whom it may concern:

Be it known that I, DAN G. SCHAFER, a citizen of the United States, residing in the county of Branch and State of Michigan, 5 have invented certain new and useful Improvements in Stanchions, of which the following is a specification.

This invention relates to cow stanchions and has for its object the production of a 10 simple and efficient cow stanchion which will be very comfortable for the cattle and which may be very readily and conveniently released when desired.

Another object of this invention is the 15 production of a simple and efficient guiding means for locking the stanchion bar as the same is being swung to and from an open position.

With these and other objects in view this 20 invention consists of certain novel constructions, combinations and arrangements of parts as will be hereinafter fully described and claimed.

In the drawings:

25 Figure 1 is a side elevation of the stanchion.

Fig. 2 is a section taken on line 2—2 of Fig. 1.

Fig. 3 is a top plan view of the stanchion,

30 Fig. 4 is a section taken on line 4—4 of Fig. 1.

By referring to the drawings, it will be seen that 1 designates the frame of a stanchion which comprises a vertical bar 2 and 35 a side inclined bar 3. The bars 2 and 3 are connected at their respective ends by means of a bottom bar 4 and a top bar 5. The side bars 2 and 3 have their respective ends seated within the notches 6 formed in the

40 top and bottom bars 4 and 5. Suitable pins 7 pass through the ends of the top and bottom bars 4 and 5 and through the bars 2 and 3 for firmly connecting the bars 2 and 3 to the respective end bars 4 and 5.

45 A locking bar 8 is pivotally mounted within the aperture 9 formed in the bottom bar 4 upon a pin 10. The upper end of the locking bar works or swings within an elongated aperture 11 formed in the top bar 5.

50 This locking bar 8 is provided with a beveled face 12 upon the upper end thereof as shown in Fig. 1 of the drawings and this beveled face 12 is adapted to force the locking link 13 to ride up over the upper end of 55 the locking bar 8, as the locking bar 8 is

swung to a closed position. This locking link 13 is pivotally held upon the top bar 5 by means of suitable anchoring staples or eyes 14.

Guiding yokes 15 are secured to the inclined side bar 3 upon opposite sides thereof, and links 16 are pivotally secured to the locking bar 8 by means of a pin 17 and these guiding links 16 extend through the guiding yokes 15 carried by the inclined bar 3. 60 65

It should be understood that the locking bar 8 may be swung inwardly by pushing upon the ends 18 of the guiding links 16 thereby relieving the operator of the necessity of pushing directly upon the locking 70 bar 8 for swinging the locking bar 8 into a closed position. The ends of the links 16 are provided with apertures 19 and are adapted to permit a tool or other suitable means to be inserted therethrough for the 75 purpose of pulling the locking bar 8 to an open position should the same become accidentally caught or rigidly held in a closed position.

Each of the bars 4 and 5 is provided with 80 a socket 20 in the outer face thereof within which socket 20 extends a link 21 of the securing chain 22, the link 21 being held in the socket 20 by means of a suitable pin 23. The chain 22 is adapted to connect the 85 stanchion to a support or other anchoring means.

The notches 6 are of greater length than the thickness of the bar 2 as shown in Fig. 3 and the top and bottom bars 4 and 5 are 90 provided with adjusting apertures 6' for receiving the pins 7 and holding the bar 2 in an adjusted position with respect to the locking bar 8.

What is claimed is:

A stanchion of the class described comprising a frame, a locking bar carried thereby, means for holding said locking bar in a closed position, guiding links connected to said locking bar, guiding yokes secured to 100 said frame, said links provided with apertures formed in the outer ends thereof for facilitating the attachment of a gripping tool for moving said links within said yokes.

In testimony whereof I affix my signature 105 in presence of two witnesses.

DAN G. SCHAFER.
